US00D980114S

(12) **United States Design Patent** (10) **Patent No.:** **US D980,114 S**
(45) **Date of Patent:** **** Mar. 7, 2023**

(54) **BUCKLE**

(71) Applicant: **Shenzhen Fengtouniao Technology Co., Ltd.**, Shenzhen (CN)

(72) Inventor: **Weiwei Qu, Fengcheng** (CN)

(**) Term: **15 Years**

(21) Appl. No.: **29/830,516**

(22) Filed: **Mar. 14, 2022**

(51) **LOC (14) Cl.** **02-07**

(52) **U.S. Cl.**

USPC **D11/200**

(58) **Field of Classification Search**
